UNITED STATES PATENT OFFICE

JOHN T. VOGEL, OF RICHMOND HILL, NEW YORK

DESIGN FOR A TABLE COVER

Application filed January 13, 1931. Serial No. 38,297. Term of patent 3½ years.

To all whom it may concern:

Be it known that I, JOHN T. VOGEL, a citizen of the United States, residing at Richmond Hill, county of Queens, and State of New York, have invented a new, original, and ornamental Design for Table Covers, of which the following description in connection with the accompanying drawing, is a specification.

The figure is a plan view of a table cover, showing my new design.

The dominant feature of the design is the incorporation therein of the twelve signs of the zodiac.

I claim:

The ornamental design for a table cover, as shown and described.

JOHN T. VOGEL.
